UNITED STATES PATENT OFFICE.

FRANK M. GRAHAM, OF OTTUMWA, IOWA.

ICE-CREAM-STORAGE CABINET.

Application filed September 27, 1927. Serial No. 222,288.

My invention relates to ice cream storage cabinets of the dry pack type, using salt and brine.

The purpose of my invention is to provide 5 an ice cream storage cabinet having a dry compartment or compartments for receiving containers for ice cream or other articles, which it is desired to keep cool or frozen, each such storage compartment being provided 10 with one or more inner walls for forming a separate narrow passage or passages inside the said storage compartment between such inner wall and the main wall, which are of less capacity than the main storage compartment, and are in communication with the 15 main storage compartment at the top and bottom thereof, whereby there is insured a circulation of air downwardly through the narrow outside passage or passages and upwardly through the main storage compartment. My cabinet has outside such storage compartment or compartments a compartment for ice, brine and the like. The ice and brine space I will call the ice and salt compartment. 20

A further purpose of my invention is to provide an ice cream storage cabinet having an ice and salt compartment provided with one or more sectional inner walls for forming 30 a separate narrow passage or passages inside the said ice and salt compartment, which are of less capacity than the main ice and salt compartment and are in communication with the main ice and salt compartment at the top and bottom thereof, whereby when sufficient 35 ice has melted to bring the level of the brine to the top of the inner sectional wall or walls there is assured a circulation of brine upwardly through the narrow passage or passages between the inner sectional wall and the outer wall of ice and salt compartment, and downwardly through the ice in the ice 40 and salt compartment.

A further purpose of my invention is to 45 provide in an ice cream storage cabinet having an ice and salt compartment a drain valve provided with a strainer whereby any undissolved salt or sediment is prevented from becoming lodged or clogged in the drain valve or pipe.

A further purpose of my invention is to 50 provide in an ice cream storage cabinet a dry storage compartment or compartments resting on or near the bottom of the cabinet, surrounded by ice, brine and the like, means for keeping the said storage compartment or

compartments from floating, which means may be anchor bars to which are attached hooks or loops which loop over the upper rim of the storage compartment or compartments, the anchor bars being fastened at both ends to fins attached to the lining of cabinet with removable pins or cotter keys. 60

Although the invention is susceptible of a variety of embodiments, it is unnecessary 65 to fully describe and illustrate more than one in order to give a full understanding of the invention both from its structural and functional standpoints.

With these and other objects in view, my 70 invention consist in the construction, arrangement and combination of the various parts of my ice cream storage cabinet, whereby the objects contemplated are attained, as hereinafter more fully set forth, pointed out 75 in my claims, and illustrated in the accompanying drawings, in which

Figure 1 shows a perspective view of an ice 80 cream storage cabinet embodying my invention.

Figure 2 is a top or plan view of the cabinet.

Figure 3 is a transverse, vertical, sectional view taken on the line 3—3 of Figure 1.

Figure 4 is a vertical, sectional view of one 85 of the storage compartments.

Figure 5 is a detail, sectional view taken 90 on the line 5—5 of Figure 3; and

Figure 6 is a detail, sectional view taken 95 on the line 6—6 of Figure 2.

Just at this time, a large number of electrical refrigerators have been put on the market. These have been very destructive to the ice refrigeration business. Electric refrigerators, however, require considerable 100 mechanical care and are relatively expensive to operate.

It is a general custom for ice cream manufacturers to supply customers with storage cabinets or refrigerators of some kind. The 105 cost of electric and mechanical refrigerators is so great that the manufacturer who furnishes them to each customer is required to invest in such refrigerators a large amount of capital.

One of the chief objections to salt and ice refrigeration arises from the fact that the ice must be changed or supplied every day.

One of the objects of the present invention 110 is to provide a structure whereby the ice and brine refrigerant may be used for a forty-eight hour period, so that the ice need not

be replaced more than once in two days. This desirable result is accomplished by the structure hereinafter more fully described.

Another objection to ice and brine refrigeration and to nearly all other types of refrigeration arises from the difficulty of maintaining the temperature at the top and bottom of the storage compartment substantially uniform.

10. In most storage cabinets the temperature is considerably warmer at the top of the cabinet.

Another purpose of my present invention is to provide means for insuring air circulation, whereby the temperature at the top and 15 bottom of the storage compartment is kept nearly the same.

In the drawings herewith, I have used the reference numeral 10 to indicate generally the main casing or cabinet having the usual 20 heat insulated walls, and having movable cover members 12 for the storage compartments.

The interior of the cabinet 10 forms an ice and brine or refrigerant compartment 14, in 25 which ice and salt may be packed. Within the compartment 14, there may be provided as many storage compartments as is desired according to the size of the entire cabinet. As shown here, I have provided two 30 storage compartments, which may have substantially the form of cylindrical containers or compartments 16. The form and construction of these compartments 16 may be varied considerably. These dry compartments 35 16 are open at the top and closed at the bottom.

It will be noted that the storage compartments 16 are arranged in the refrigerant compartment in such manner that the ice and 40 brine will entirely surround each storage compartment.

It is obvious, however, that the results I desire to attain could be secured in a substantial degree if the ice and salt compartments 45 did not extend entirely around the dry storage compartments.

Each dry storage compartment 16 has an inner wall 18 terminating above the bottom and below the top of the compartment 16.

50. The wall 18 is spaced from the inner face of the wall of the compartment 16, except at their side edges, which are secured to the walls of the compartment 16.

Thus between the walls 18 and the walls of 55 the compartments 16 are formed narrow passages 20 on one side of each dry storage compartment. The number of such passages 20 could, of course, be varied and any structure adapted, square, round or oblong, with the 60 inner wall 18 spaced from the outer wall of the compartment 16.

The passage 20 may extend part way or 65 entirely around the inside of the wall of the compartment 16, forming the narrow passage or passages in communication with the

storage compartment and arranged to permit the air to pass freely over the top and under the lower edge of the wall or walls 18 to and from the storage space.

It is particularly to be noted that the capacity of the passage or passages formed between the wall or walls 18 and the wall of the storage compartment is less than the capacity of the storage compartment 16. This is a matter of importance for reasons which 75 will now be set forth.

In the practical use of my improved ice cream storage cabinet, ice cream cans 22, bricks of ice cream or other articles which are to be kept cool are placed in the storage compartments 16, after the ice and salt compartment has been filled with cracked ice and salt.

The construction of my ice cream cabinet is such that when the ice and salt have been placed in the ice and salt compartment, and the material to be cooled is placed in the storage compartments, and the covers 12 replaced on the cabinet, the desired air circulation will be created for affording a maximum cooling of the ice cream or other articles in the storage compartments with approximately uniform temperature through the entire depth of the storage compartments with a minimum consumption of ice and salt.

A circulation of air will be immediately created downwardly through the narrow passage 20 between the walls 18 and the walls of the storage compartments, thence around the bottom of the walls 18, and thence upwardly through the storage compartment 16 around the articles which are to be kept cool. This circulation of air is accomplished by the construction to which attention will now be called and has the advantages hereinafter 105 more fully referred to.

Because of the fact that the capacity of the passage 20 is less than the capacity of the compartment 16 and because of the further fact that the cooling surface exposure in the 110 passage 20 is greater with relation to the volume of air therein, than is the cooling surface of the compartment 16 with relation to the air therein, and the fact that the air in the compartment 16 is subject to the warming influence from the articles stored therein, the relatively small amount of air in the passage 20 will be quickly cooled and will drop. The slightly warmer air around the articles in the storage compartment will rise 115 as a result of the greater specific gravity of colder air in the passage 20.

When ice cream in relatively tall cans is placed in the storage compartment, the warmer air in the compartment will 120 obviously be at the upper part of the compartment 16.

On account of the circulation of air which is immediately established owing to the features of construction already mentioned, it 130

is obvious that this warm air instead of remaining at the top of the storage compartment, as would be the case in the absence of such structure or other means of creating a circulation of air within the storage compartment 16, will be drawn into the outer passage 20 and cooled in the downward movement therethrough by coming in contact with the cooling wall.

10 The air will pass around the bottom of the wall 16 and upwardly again around the articles stored, as it becomes slightly warmer and loses a portion of its specific gravity.

Thus the temperature at the top and bottom of the storage compartment will be kept at about the same degree, which is of great importance.

Another purpose of my invention is to provide an ice cream storage cabinet that will maintain sufficiently low and uniform temperature for a longer time without re-icing, thereby reducing the labor and trucking cost of servicing such cabinets. This purpose is attained by providing a structure which causes a circulation of the brine at a predetermined time when the cabinet is likely to be losing its refrigeration. The circulation of brine is created by means of the sectional wall or walls 24, (Figures 2 and 3), spaced from the outer wall of the ice and salt compartment. The wall 24 may be slidably mounted in guides 24^a which frictionally engage wall 24 as shown to hold it in any adjusted position.

35 The wall 24 holds the ice away from the narrow passage 26, formed between it and the wall of the compartment 14. Brine, however, will flow into this narrow passage and be in contact with the warmer outer wall of the ice and salt compartment 14, and will become warmer and rise. The colder brine in the ice and salt compartment will drop in proportion to the amount of brine rising through the passage 26.

45 When the brine reaches the top of the inside sectional wall 24, there will immediately be established a circulation of the brine upwardly through the narrow passage 26, over the upper edge of the sectional wall 24, and downwardly through the ice in the ice and salt compartment 14.

The ice at which this circulation of brine is created is governed by the height of the sectional wall 24.

55 By adjusting the height of the sectional wall 24 to the approximate level of the brine resulting from the melting of the ice during the first eighteen to twenty-four hours after an icing, there will at that time be immediately established a circulation of brine which has the effect of putting new life into the refrigeration by the brine passing through the remaining unmelted ice in the ice and salt compartment.

65 It is obvious that the articles stored in

the compartments 16 will be benefited by the improved refrigeration.

By adjusting the wall 24, the device may be adapted to provide for the commencement of the brine circulation at the right time in different seasons or climates.

The ice and salt compartment 14 is provided with a drain pipe 28, leading from its lower part through the wall of the cabinet 10. A control cock 30 is provided for controlling flow through the pipe 28, and thus for permitting the draining and flushing of the compartment 14.

As a means for preventing the pipe 28 or cock 30 from becoming clogged with undissolved salt or sediment, I install a removable metal strainer 32 in front of the inner end of the drain pipe. This strainer extends from near the top of the ice and salt compartment to the bottom and is spaced from the ice and salt compartment wall to leave sufficient clearance in front of the drain pipe 28.

The strainer 32 has side flanges 32^a, which travel in guides 34, so that the strainer may be removed by lifting it upwards.

By extending this strainer 32 practically the full depth of the storage compartment and providing the series of small strainer holes from top to bottom, it is obvious that a free and uninterrupted outlet to the drain pipe 28 will be effected even though considerable undissolved salt or sediment may have collected in the bottom of the ice and salt compartment.

This is of considerable importance for the reason that in the absence of some such strainer attachment in draining cabinets, it is a usual occurrence for the drain pipes to become clogged and in opening them up more or less brine is spilled on the floor of the stores in detriment to the popularity of the ice and salt cabinets.

My storage compartments 16 are simply set into the ice and brine compartment, so that the storage compartments may be lifted out for cleaning or repair purposes.

With such construction, means must be provided for preventing the members 16 from floating. In my invention this is provided for by means of anchor bars 36, extending lengthwise of the ice and brine compartment near each side. These bars 36 preferably have bifurcated ends 36^a, which may be secured to brackets 38 on the storage compartment walls by pins or cotter keys 40.

The bars 36 carry hooks 42 for coacting with the tops of the compartments 16 for holding the compartments down. Upon removing the pin or cotter key 40 at one end of each anchor bar, the bars can be swung up and the storage compartments can then be lifted out, leaving easy access to the ice and salt compartment for thorough cleaning.

While I have illustrated in my drawings one particular form in which the invention may

be embodied, I realize that the device may be made in a variety of forms and it is not my intention to limit myself to the particular form here disclosed, but it is my intention to cover by my claims any modified forms of structure or use of mechanical equivalents, which may be reasonably included within their scope.

I claim as my invention:

10. 1. In a storage cabinet, a cabinet having a refrigerant compartment, a plurality of storage compartments therein, each having on its interior a wall spaced from its main wall, terminating above the bottom and below the top of the storage compartment and forming with the main wall a narrow passage of less capacity than the remaining interior of the storage compartment, whereby air circulation from top to bottom will be provided in that passage and from bottom upward through the storage compartment.
20. 2. In a storage cabinet, a cabinet having an ice and brine compartment, a plurality of storage compartments therein detachably resting on the bottom of the ice and brine compartment, and a locking bar removably supported in the first compartment having means for engaging the several storage compartments for holding them down whereby the said compartments may be locked down or released by movement of said means.
30. 3. In a storage cabinet, a cabinet having an ice and brine compartment, a plurality of storage compartments therein detachably resting on the bottom of the ice and brine compartment, and a pivoted bar supported in the first compartment and having means for engaging the several storage compartments for holding them down, and means for locking said bar in operative position.
40. 4. In a storage cabinet, a cabinet having an ice and brine compartment provided with an inner wall spaced from its main wall, ter-

minating a short distance above the bottom and substantially below the top of such compartment, whereby there is provided a narrow, vertical brine passage, said inner wall being vertically adjustable.

5. In an ice cream storage cabinet having an ice and brine compartment with a drain pipe leading from its lower part, vertical guides attached to the ice and brine compartment wall, a removable strainer fitted in said vertical guides for forming a narrow passage from top to bottom of the ice and brine compartment in front of drain pipe whereby a free passage of brine to the narrow passage and the exclusion of large particles therefrom is effected.

6. In a storage cabinet, a cabinet having a refrigerant compartment, a plurality of storage compartments therein detachably resting on the bottom of the ice and brine compartment, pivoted bars supported in the first compartment and having means for engaging the storage compartments for holding them down, means for locking said bars in operative position, each of said compartments having on its interior a wall spaced from its main wall, terminating above the bottom and below the top of the storage compartment and forming with the main wall a narrow passage of less capacity than the remaining interior of the storage compartment, whereby air circulation from top to bottom will be provided in that passage and from bottom upward through the storage compartment, said ice and brine compartment provided with an inner wall spaced from its main wall, terminating a short distance above the bottom and substantially below the top of such compartment, whereby there is provided a narrow, vertical brine passage, said inner wall being vertically adjustable.

Des Moines, Iowa, September 8, 1927.
FRANK M. GRAHAM.
